J. W. WILLIAMS AND C. A. PARKER.
AUTOMATIC ELECTRICALLY CONTROLLED RAILWAY TRAIN STOPPING SYSTEM.
APPLICATION FILED OCT. 29, 1918.

1,323,944.

Patented Dec. 2, 1919.

UNITED STATES PATENT OFFICE.

JAMES W. WILLIAMS, OF SPOKANE, WASHINGTON, AND CHARLES A. PARKER, OF HAUGAN, MONTANA.

AUTOMATIC ELECTRICALLY-CONTROLLED RAILWAY-TRAIN-STOPPING SYSTEM.

1,323,944.

Specification of Letters Patent.

Patented Dec. 2, 1919.

Application filed October 29, 1918. Serial No. 260,096.

To all whom it may concern:

Be it known that we, JAMES W. WILLIAMS, of Spokane, in the county of Spokane and State of Washington, and CHARLES A. PARKER, of Haugan, in the county of Mineral and State of Montana, have invented certain new and useful Improvements in Automatic Electrically-Controlled Railway-Train-Stopping Systems, of which the following is a specification.

The system in which our invention is comprised is one in which the train-brake-valve operating devices are controlled from a track or signal battery, through the intermediary of devices called into action when the train is entering a block under abnormal or dangerous conditions; and it consists in certain improvements for this purpose which will first be described in connection with the accompanying drawing forming a part of this specification, and will then be more particularly pointed out in the claims.

The drawing is a diagrammatic illustration of our invention.

1 is the locomotive and 2 is the track on which it runs. The latter is supposed to be divided into insulated blocks as customary, with a signal post S and usual signal appliances such as the semaphore arm, etc., at or near the entrance to each block. At this point also are located along side the track a ramp rail 5, and a contact rail 6. On the locomotive is a contact shoe 7 mounted thereon so as to be capable of vertical movement with reference thereto, and adapted, in passing the contact rail and the ramp rail, to make contact with the former and to ride over the latter, the shoe being pressed by weight, or equivalent yielding pressure, to occupy normally its low position. The up and down movements thus imparted to the shoe are utilized to operate a cock 14 on a pipe leading from the main compressed air reservoir R on the locomotive. For this purpose the shoe is connected to the handle 13 on the cock by suitable intermediaries typified by the vertical connecting rod 12. 3 is the track or signal battery; one of its terminals 8 is connected to the track, and 50 the other 9 to the contact rail 6, this portion of the circuit being completed through a pair of contacts 4 having connections where-

by they remain open so long as the signal is at danger, but are caused to close and remain closed whenever and so long as the signal is at safety, as indicated diagrammatically in the drawings wherein one of the contacts 4 is conventionally represented as carried by the hub of the semaphore arm in position to be closed upon the other contact 60 only when the semaphore arm is at safety as shown.

The circuit connections lead from the 8 side of battery 3 through the track and locomotive wheel, through wire 10, through 65 spool of electro-magnet N, through wire 11 to and through rod 12 and shoe 7, thence to contact rail 6, and thence through wire 9 and contacts 4 back to battery.

Under this arrangement whenever and so 70 long as the circuit just traced is interrupted, the electro-magnet N located on the locomotive and included in that circuit will be inactive.

The pipe 15 leads from the main reservoir 75 R into a chamber 16, containing a suitable valve—in this instance a soft iron ball valve 17—below the core n of the electro-magnet N. This core is tubular as shown and its open lower end is armed with a port 18 80 adapted to be closed by the ball valve 17, when the latter is attracted by the core of the electro-magnet. The port should be provided with a non-magnetic bushing to prevent the direct contact of the ball valve 85 with the core, and the consequent temporary sticking of the valve to the core after the magnet ceases to be energized.

The tubular core n serves as a conduit for the air led through the pipe 15 into the 90 chamber 16, and at its upper end it is connected to a pipe 19 which leads into the top of a cylinder 20 above a vertically reciprocable piston 21 contained in said cylinder. The piston rod 22 of said piston projects 95 through the lower head of the cylinder 20 and is suitably jointed to the handle 23 of a controlling valve 24 in a pipe 25 leading from the main reservoir R. In the position of the parts shown in the drawing the valve 100 24 is closed. If, at the time the shoe on the engine is lifted by the ramp rail with consequent opening of the cock 14 on branch pipe 15, the working circuit including the

magnet N is closed, the ball valve 17 will be attracted by its magnet consequently closing the port through which the air passes to the cylinder 20, the piston 21 will remain at rest, 5 and the valve 24 will remain closed. Should however the working circuit at this time be not completed, the magnet N would remain inactive, the ball valve consequently would not be attracted, and the port controlled by 10 it would be open to the passage of the compressed air to and through the branch pipe continuation 19, into the cylinder 20 above the piston therein, with the effect of depressing the latter and consequently opening the 15 valve 24. The piston when thus depressed will remain in that position even after the air pressure upon it from above through the pipe 19 is cut off. Its return to its upper position is effected by hand operated instrumentalities, for which purpose we connect the cylinder 20 with the pipe 25, through a branch 26 which opens into the cylinder at a point below the piston when the latter is in its depressed position; the flow of air through 25 said branch from the pipe 25 into the cylinder 20 being controlled by a hand operated valve 27, the operating handle 28 of which is located in practice in the locomotive cab within convenient reach of the engineer.

30 The train pipe p is the usual service pipe in air brake systems which extends from the engineer's air brake valve P in the engine cab to the rear end of the train. Interposed in the train pipe is a valve chamber 35 29 having two ports 30 and 31 controlled by a valve 32 normally upheld to close the upper port by a spring 33 surrounding the valve stem 34 passing through a guide 35 in the valve chamber and provided at its 40 upper end with a piston 36. The normally open lower port 31 is the passage through which the train pipe leads to the engineer's brake valve P. The valve 32 when depressed against the stress of its spring will 45 close the port 31 and at the same time open the upper port 30 through which communication from the train pipe will be established with a vent pipe 37 discharging into atmosphere, its vent being controlled by 50 an automatic relief valve E adjustable to open at any desired pressure.

The air pipe 25, leading from the main reservoir R and provided with the controlling valve 24 as hereinbefore mentioned, enters at its other end the valve chamber 29 above the piston 36 therein. The valve 24 normally closes the pipe 25 against the passage of air therethrough; when however it is automatically operated by the non-energizing of the electro-magnet N as hereinbefore indicated it will throw open the pipe 25 so that air under pressure may pass therethrough into the top of valve chamber 29 above the piston 36 therein thus forcing 60 said piston and consequently its valve

32 down to close the port 31 leading to the engineer's brake valve P and opening the port 30 leading to the vent branch p' of the train pipe p —substantially as set forth in Patent No. 1,237,594 of August 21, 1917 70 granted to James W. Williams one of the applicants named herein.

Under the arrangement thus far described it will be noted that if for any reason whether because of abnormal circuit conditions or for any other causes, electrical or mechanical, the electro-magnetic ball check valve 17 should fail to operate to close the passage controlled by it at the time the shoe 7 on the locomotive is lifted by its passage 80 over the ramp rail 5 to momentarily effect the opening of the valve to which it is connected, the controlling valve 24 will at once be thrown open for the passage of air under pressure to the valve chamber 29 and the consequent application of the train brakes; and the parts will remain in the position to which they have been thus brought until said valve 24 is closed by hand—in this instance through the instrumentality of the hand operated valve 27, 28 in the engine cab.

In order to prevent the train from proceeding in case the contact shoe 7 should be broken off by rock or other obstructions 95 that might, by accident, or otherwise, lay along side the running rail in the path of the shoe, means are provided whereby the valve 14 controlled by said shoe shall, in any such event, be at once automatically opened, with the effect, as already explained, of applying the train brakes. To this end we provide, in the present instance, an arm 44 hinged at one end to a bracket or base 45 secured at a suitable point to the locomotive, and at the other end to a collar 46 on the rod 12 which connects the shoe with the valve 14; and between the arm 44 and a stationary bearing properly located on the locomotive we interpose a spring 47, which 100 normally presses the hinged arm 44 and consequently the connecting rod 12 in a direction to open the air valve 14. The weight of the shoe so far preponderates as to hold the valve 14 closed against the pressure of spring 47. Should however the shoe from 110 any cause be broken off or otherwise separated from the rod 12, the spring would at once act to move the rod 12 in a direction to open the valve 14, with the effect of immediately applying the train brakes.

In order to provide means for effecting an "emergency stop" after the valve 32 has been automatically operated as above described to give a "service stop", a by-pass pipe 38 leads from the pipe p at a point between the valve chamber 29 and the engineer's brake valve P, and opens into the lower part of the piston chamber of valve 32; a self closing ball valve 39 is located 130

at the junction of the by-pass pipe 38 with the train pipe p . Under this arrangement the engineer through his regular brake valve P , by way of the by-pass 38, quickly 5 reduces the train pipe pressure to the desired point, the valve 39 rising to permit free communication between the by-pass and train pipe. When the engineer is operating the train and handling the air through port 10 31 the pressure in the train pipe will be on valve 39 from above, thus holding it in position to close the by-pass 38.

In connection with the train stopping system hereinbefore described we make use of 15 an electrical signal system installed on the locomotive and intended to indicate to the engineer the track signal conditions, as well as the condition of the train stopping system.

20 To this end we place in some convenient place, preferably the engine cab where they can be seen by the engineer, two electric lights, a green and a red light, for safety and danger respectively, and connect them up in circuit with a battery on the train in 25 such manner that they shall properly respond to the conditions of the stopping system. In the arrangement shown in the drawing for this purpose B is the battery; 30 g is the circuit including the green light G , completed through a pair of normally open contacts a ; and r is the circuit including the red light R , completed through a pair of normally open contacts b . The contacts in the safety circuit g are controlled 35 by the stem 39 of a normally spring-lifted piston 40 contained in a cylinder 41 located beneath the ball valve chamber 16, and communicating therewith through a passage 42 closed by the ball valve 17 when in its low 40 position as shown in the drawing. A small opening 43 in the side of the cylinder 41 at a point above the piston 40 is provided to permit leakage of air from above the piston 45 after it has depressed the piston to cause the piston stem 39 to close the contacts a , and thus allow said piston to be returned by its spring to its normal lifted position.

The contacts a of the green light circuit g 50 are closed only when the circuit condition of the track circuit on the train entering a block are at safety. And when thus closed the green light included in the circuit is active. The contacts b in the danger circuit 55 r are controlled by the stem 22 of the piston 21, which when it moves downward—as it does whenever the track circuit is not closed while the shoe 7 is passing over the ramp rail 5—to open the controlling valve 24, 60 with consequent application of the train brakes, also operates to close the contacts r of the red light circuit r thus completing said circuit and consequently displaying the red light R .

65 Having described our improvements and

the best way now known to us of carrying the same into practical effect we state in conclusion that we do not limit ourselves narrowly to the specific details hereinbefore set forth in illustration of our invention for 70 manifestly the same can be varied to some extent without departure from the spirit of the invention; but what we claim and desire to secure by Letters Patent is as follows:

1. Train stopping mechanism comprising a train pipe, a vent from the train pipe, a normally closed valve controlling a port through which the train pipe communicates with said vent, a pipe leading from a compressed air reservoir on the locomotive and opening into the valve chamber containing said valve, instrumentalities in said valve chamber adapted to be operated by the air pressure admitted through said pipe to actuate said valve to open the port controlled by it, and a normally closed valve in said compressed air pipe controlling the admission of the air to said valve chamber, in combination with the following instrumentalities, namely: a track or signal battery; a working circuit therefrom completed through contacts on the locomotive and track respectively at the entrance to a block, and including a pair of normally open contacts; a track signal and means whereby said normally open contacts are closed whenever and so long as the signal is at safety; a train stopping electro-magnet in said working circuit and located on the locomotive; 100 an air cylinder, and piston and means connected with said piston for operating the valve on the pipe admitting air to the vent controlling valve of the train stopping mechanism; a branch pipe leading from the compressed air reservoir to the air cylinder last named; a valve in said branch pipe controlled by said train stopping electro-magnet, and acting whenever and so long as said magnet is energized to close said branch 105 air pipe; a normally closed cock on said branch pipe between the said electro-magnetically controlled valve and reservoir; and means called into action by a passing train 110 at the entrance to a block to momentarily open said cock.

2. The combination with the subject matter of claim 1 of hand operated means whereby the controlling valve on the pipe conveying compressed air to the valve chamber of the train stopping mechanism may be returned to closed position.

3. In combination with the subject matter of claim 1 a battery on the locomotive, two branch circuits therefrom completed each through a pair of normally open contacts and including the one a safety and the other a danger signal energized by the closing of the circuit in which it is included, and means whereby one or the other of said pairs of 125

130

contacts is closed when the train is entering a block, according as the working circuit at that time is open or closed.

4. The combination of elements specified in claim 1 when the means called into action by the passing train at the entrance to a block to momentarily open the cock which controls the passage of air through the branch pipe between the electrically controlled valve and air reservoir comprise a track ramp rail a shoe on the locomotive adapted to be momentarily lifted by its passage over the ramp rail, and connections
- 5
- 10

between said shoe and cock on said branch pipe whereby the lifting of the shoe effects 15 the opening of the cock.

5. The combination with the subject matter of the last preceding claim of means whereby the air cock shall be automatically opened in event of the detachment of the 20 shoe from the means which connect it to said air cock.

In testimony whereof we affix our signatures.

JAMES W. WILLIAMS.
CHARLES A. PARKER.
